UNITED STATES PATENT OFFICE.

JAMES L. LOVE, OF GAINESVILLE, TEXAS.

FLYING-MACHINE.

988,794.

Specification of Letters Patent.

Patented Apr. 4, 1911.

Application filed November 21, 1910. Serial No. 593,555.

To all whom it may concern:

Be it known that I, JAMES L. LOVE, a citizen of the United States, residing at Gainesville, in the county of Cooke and State of Texas, have invented certain new and useful Improvements in Flying-Machines; and I do hereby declare the following to be a full, clear, and exact description of the invention, such as will enable others skilled in the art to which it appertains to make and use the same.

This invention relates to new and useful improvements in flying machines, and more particularly to that type which are heavier than air and depend for their lifting capacity upon the reaction of air against inclined planes when the machine is propelled through the air.

The object of this invention is to improve and simplify devices of this character rendering them comparatively simple and inexpensive to manufacture, reliable and efficient in use and readily operated.

With these and other objects in view, the invention consists in certain combinations and arrangements of the parts as will more fully appear as the description proceeds, the novel features thereof being pointed out in the appended claims.

Figure 1 is a side elevation of my improved air ship and Fig. 2 is a plan view thereof with the upper plane removed.

Referring to the drawings by characters of reference, the numeral 1 designates generally a main frame comprising opposite end members 2 and 3 connected by horizontally disposed transverse members 4, while these end members 2 and 3 are connected at their upper and lower edges by longitudinally extending rods or bars 5. The transverse connecting members 4 in the opposite ends of the frame, together with the longitudinally extending rods 5 are covered by a suitable stationary plane 6, upon which are mounted the operating means, together with seats 7.

An engine 8 is suitably supported upon the lower portion of the frame 1, and is provided with means for driving a propeller shaft 9 upon the rearwardly extending end 50 of which is keyed or otherwise secured a propeller blade 10, which is adapted to drive the machine.

A vertically disposed rudder 11 is mounted upon a vertical axis in suitable bearings 12, secured to one of the vertical rods in the end member 2, while a suitable pulley 13 is

secured to one of the adjacent vertical rods, over which passes a cable 14, one end of which is secured to the end of the rudder 11, while the other end is secured to an arm 15, carried by a longitudinally and horizontally disposed shaft 16, mounted in a suitable bearing 17 secured to the frame 1 in any suitable manner, while the opposite end of the shaft 16, to which the arm 15 is secured is provided with a hand wheel 18, whereby the said shaft 16 may be rotated so as to swing the arm 15 and move the rudder 11 for the purpose of steering the machine either to the right or left as desired. A spring 19 which connects the end of the rudder 11 to one of the upright rods of the end 2, serves to return the rudder to its normal position after the machine has been turned.

The vertical rods composed in each of the end members 2 and 3 are connected at their intermediate portions by transverse bars 20, to which are hinged, elevating planes 21, to the inner ends of which are attached the cables 22 which pass over pulleys 23 and 24 mounted upon the top and bottom of the frame 1 respectively, and passing at points substantially intermediate of their lengths around arms 25, mounted upon shafts 26, supported by suitable bearings 27 and 28, adapted to operate so as to tilt the plane vertically as desired, at the will of the operator, by means of suitable hand wheels 29, which are keyed to the shaft 26 which operation obviously causes the machine to either ascend or descend as the said planes are tilted in either direction.

Upwardly extending standards 29 are pivotally connected to the frame 1 and pivotally support at their outer extremities substantially rectangular curved frame 30, to which is secured an upwardly convexed plane 31, to the opposite ends of which are secured cables 32, which pass over pulleys 33, secured to the lower portions of the end members 2 and 3 after which they converge so that they may be connected to single cables 34, the opposite ends of which are secured to the lower end of a lever 35 which is mounted at 36 for engagement with a rack 37, so that as the lever is swung in either direction, the opposite ends of the curved plane 31 will be tilted in order that it may assist the machine to either ascend or descend.

From the foregoing disclosure taken in connection with the accompanying drawing

it will be manifest that a flying machine is provided for that will be very easily controlled, and that will fulfil all the necessary requirements of such a device.

5 Having thus fully described this invention, what I claim as new and desire to secure by Letters Patent is:

1. In a flying machine the combination of a main frame, having cross bars extending across the top at mid length and at the ends thereof, propelling means mounted on the frame, a main plane secured to the lower portion of the frame, a movable plane located above the main plane and supported by standards, each having one end oscillatably mounted upon a cross bar of the main frame, and the other end similarly mounted upon a correspondingly situated cross bar of the movable plane, cables upon the main frame and connected to a propelling lever and to the opposite ends of the before-mentioned main plane for the purpose of tilting the same, a vertical rudder, a rock shaft upon the main frame and operatively connected to the said vertical rudder, a series of auxiliary planes secured to each end of the main frame, and means for tilting the auxiliary planes independently of each other for the purpose of balancing the flying machine, substantially as and for the purposes set forth.

2. In a flying machine the combination of a main frame, having cross bars extending across the top at mid length and at each end thereof, propelling means mounted on the main frame, a main plane secured to the lower portion of the frame, a movable plane above the main plane and supported by standards, each having one end oscillat-

ably mounted upon a cross bar of the main frame and the other end similarly mounted upon a correspondingly situated cross bar of the movable plane, cables upon the main frame and connected to a propelling lever and to the opposite ends of the before-mentioned main plane for the purpose of tilting the same, a vertical rudder, a rock shaft upon the main frame and operatively connected to the said vertical rudder, a series of auxiliary planes secured to each end of the main frame, and means for tilting the auxiliary planes independently of each other for the purpose of balancing the flying machine, substantially as and for the purposes set forth.

3. In a flying machine, the combination of a main frame, propelling means mounted thereon, a stationary plane secured to the lower end of the main frame, a movable plane secured to the upper end of the main frame, balancing means carried by the main frame, a vertical rudder mounted to turn about a vertical axis, a rock shaft provided with a lateral arm, and cables producing an operative connection between the said arm and vertical rudder for turning the latter.

In testimony whereof I affix my signature in presence of two witnesses.

JAMES L. LOVE.
